UNITED STATES PATENT OFFICE

LUKE CAKMO, OF CHICAGO, ILLINOIS

CELLAR DRAIN

Application filed December 28, 1929. Serial No. 417,164.

The present invention relates to drains and more particularly to drains adapted to be mounted in cellars or the like.

An object of this invention is to provide a drain structure which may be readily mounted in the floor of a cellar or the like and which is adapted to be used for preventing flooding of the cellar.

Another object of this invention is to provide a device of this character which is normally in inoperative position but which is adapted to be manually controlled when the water seeps into the cellar.

A further object of this invention is to provide a device of this character which is of simple construction and may be readily and cheaply manufactured.

The above and various other objects and advantages of this invention will in part be described in and in part be understood from the following detailed description of the present preferred embodiment, the same being illustrated in the accompanying drawing wherein:

Figure 1 is a longitudinal section, partly in detail, of a device constructed according to the preferred embodiment of this invention in closed position;

Figure 2 is a detailed side elevation, partly in section, of the device in open position; and

Figure 3 is a detailed top plan view of the device.

Referring to the drawing wherein like numerals of reference designate corresponding parts throughout the several views, the numeral 10 designates a floor or the like of a cellar or other structure where water is more apt to accumulate, particularly during rainy seasons or in the spring after thawing or melting of the snow or the like.

In a great many communities the regulations will not permit an open drain being mounted in a cellar or other closure and in order to drain off any water which occasionally seeps into cellars or the like a drain member 11 is adapted to be sunk or embedded in the floor of the cellar. The drain member 11 is of annular construction and is provided with an annular inwardly extending valve seat 12. The upper edge portion

of the drain member 11 is adapted to be mounted substantially flush with the floor of the cellar and may be connected at its lower end by suitable drain pipes or the like with the drainage or other carry-off system.

A substantially U-shaped standard 13 which is provided with outwardly extending lug members 14 is adapted to be mounted on the floor 10 in upstanding position and held upright by means of bolt or securing members 15 which are adapted to extend downwardly into the floor of the cellar. The upper end portion of the standard 13 is provided with an enlarged apertured central portion 16 which is preferably threaded so as to threadably receive a screw member 17. The screw member 17 is provided at the lower end portion thereof with an annular groove 18 which is adapted to loosely receive an apertured plate member 19. The plate member 19 is bolted or otherwise secured to a swiveled closure member 20 which is preferably of annular construction and is provided with an outstanding flange 21.

The outstanding flange 21 is adapted to engage the valve seat 12 and a gasket 22 is interposed between the lower face of the annular flange 21 and the seat 12 and is carried by the plate member 20 so as to effectively close the drain 11 and prevent any gases or the like from escaping upwardly through the drain and into the cellar. The plate member 20 is preferably provided with a downwardly extending annular flange or ring 23 which is adapted to be mounted in the neck 24 of the drain 11 so as to cooperate with the annular flange 21 in effectively sealing the drain 11.

The upper end portion of the screw member 17 is preferably provided with a squared or restricted portion 25 for receiving a wheel or operating member 26 which may be secured to the operating screw 17 in any suitable manner.

In the use of this device, the drain member 11 is adapted to be sunk into the concrete of the cellar or the like, the upper edge portion of the drain being substantially flush with the floor of the cellar so as to permit any water in the cellar to pass downwardly

through the drain. The standard 13 is preferably mounted in substantially upright or vertical position on the floor of the cylinder and is preferably positioned so that the axis 5 of the operating member 17 is concentric with the axis of the drain so that the plate or closure member 20 will readily seat in the tapering upper end portion of the drain 11. The closure member 20 is adapted to be normally seated in the drain 11 but when water 10 or the like begins to seep into the cellar, the screw member 17 may be turned so as to withdraw the plate 20 from the seat 12 of the drain 11 thereby permitting the water 15 to pass downwardly therethrough.

It will, of course, be understood that various changes and modifications may be made in the details of construction and design of the above specifically described embodiment 20 of the invention without departing from the spirit thereof, such changes and modifications being restricted only by the scope of the following claim:

What is claimed is:—

25 A valve of the character described comprising a valve seat adapted to be countersunk in a floor, a standard overlying said valve seat, an annular closure member, said annular closure member comprising a plate, 30 an annular outstanding flange, an annular depending flange secured to said plate, and operating means for said closure member, said operating means comprising a screw member engaging said standard, said screw member having an annular groove spaced upwardly from the lower end thereof, an apertured plate adapted to loosely engage said screw in said annular groove, means for mounting said apertured plate on said closure member, and operating means for said screw.

In testimony whereof I hereunto affix my signature.

LUKE CAKMO.
